BOAT

Robert Cohen, P.O. Box 14368, Houston, Tex.

Filed Oct. 19, 1959, Ser. No. 57,975

Term of patent 14 years

(Cl. D71—1)

FIGURE 1 is a front perspective view of a boat showing my new design.

FIGURE 2 is a rear perspective view thereof.

FIGURE 3 is a top plan view of the boat.

FIGURE 4 is a right side elevation of the boat. The left side thereof is a mirror image of the side shown.

FIGURE 5 is an elevational view of the front of the boat.

My design for the disclosed boat is characterized by the forwardly inclined, cantilevered canopy member.

I claim:

The ornamental design for a boat, as shown and described.
